ATTORNEY

UNITED STATES PATENT OFFICE.

PHILIP MURTHA, OF PHILADELPHIA, PENNSYLVANIA.

SHOE-MAKER'S ANVIL.

SPECIFICATION forming part of Letters Patent No. 396,106, dated January 15, 1889.

Application filed August 20, 1888. Serial No. 283,229. (No model.)

To all whom it may concern:

Be it known that I, PHILIP MURTHA, a citizen of the United States, residing at Philadelphia, in the county of Philadelphia and State 5 of Pennsylvania, have invented certain new and useful Improvements in Shoe-Makers' Anvils, of which the following is a specification.

My invention has relation to shoe-makers' portable anvils, and it has for its object simplicity of construction, convenience in using the same, and durability; and it consists in the combinations, constructions, and arrangements of parts, as hereinafter described in the specification and pointed out in the claims, 10 reference being had particularly to, preferably, a wood standard having on its bottom a cushion of rubber or like material and one or more laterally-projecting extended feet, and at its top a set-screw and a removable anvil-block which is retained in position by the set-screw.

Referring to the accompanying drawings, Figure 1 is a perspective of a shoe-maker's anvil embodying my improvements. Fig. 2 is a 15 transverse section of the removable anvil-block, set-screw, its bearings, and the top part of the standard. Fig. 3 is an elevation of same, partly broken away; and Figs. 4 and 5 are respectively a side elevation and a plan 20 of a removable anvil-block shaped to be inserted in a shoe or boot when heelng the same.

A represents the portable anvil, composed of a standard, B, which is preferably made of wood to secure a light-weight anvil for convenience of handling the same, and has affixed to its bottom in any suitable manner a cushion of rubber or other suitable material, a, to absorb or take up the noise and vibrations incident to hammering upon the anvil.

Secured to the sides of the standard are, 35 preferably, two laterally-projecting feet, C, located at about right angles to each other, and are of an extended length. They may be made of any suitable material and of any desired configuration; but for economy, lightness, and effectiveness in using the anvil I prefer to make the feet C of strip-iron and screw one of their ends, c, to the standard, locate their horizontal parts c' above the bottom of the standard, and so bend the outer ends, c', thereof that they curve above the

horizontal parts c', as indicated at c³, and then assume a vertical position to form a three-part or tripod support for the anvil, so that it always finds its level or position, irrespective 55 of the condition of the floor or support upon which it is placed. The feet C are shaped to have the extended flat or horizontal parts c', to admit of the shoe-maker placing his feet on the same to firmly hold the anvil in position while hammering, and the curved or raised parts c³ are provided to prevent his feet slipping off the same and to give necessary purchase to keep the anvil rigid while hammering on it.

The top of the standard is preferably slotted transversely, as indicated at d, which communicates with a vertical recess, d', in one side of the standard. In these recesses d d' is inserted a right-angle bracket or clip, D, 70 having a threaded opening, d², in its horizontally-located limb d³ and openings d⁴ in its vertical limb d⁵, through which pass screws or other fastening devices d⁶, for securing the bracket or clip D to the top of the standard. 75

In the threaded opening d² is inserted a set-screw, d⁷, having a thumb-piece or end, d⁸, and an annular collar or washer, d⁹, in front of the same.

The anvil-block F may be of any suitable 80 shape as required by the character of the work to be done, and is formed with a socket, f, in its lower end corresponding to and fitting the top of the standard. In one side of said socket is a vertical slot, f', into which the set-screw d⁷ 85 passes when the block F is adjusted upon the top of the standard, and by turning the set-screw until its collar d⁹ binds against the outer adjacent surface of the anvil-block socket f the block is rigidly held to the standard, and 90 is removable therefrom by simply loosening screw d.

In using the foregoing-described anvil it is placed, preferably, upon the floor adjacent to the shoe-maker's bench, so that when using it 95 he can conveniently place his feet upon the horizontal parts c' of the standard-feet C to keep the anvil rigid, and also admit of readily turning the anvil around as the requirements of the work demand.

What I claim is—

1. A shoe-maker's anvil, herein described,

comprising a standard having at its upper end a set-screw and at its lower end laterally-projecting feet having curved or raised outer ends, and removable anvil-blocks secured to said standard by said set-screw, substantially as set forth.

2. A shoe-maker's anvil comprising a standard having at its upper end a set-screw, d' , removable anvil-block F, and at its lower end a cushion, a, and laterally-projecting feet C, having raised or curved ends c^3 , substantially as set forth.

3. In a shoe-maker's anvil, the combination

of standard A, having at its upper end a bracket or clip, d , the anvil-block F, having 15 socket f and vertical slot f' , a cushion, a, on the lower end of said standard, and laterally-projecting extended feet C, having raised or curved ends c^3 , substantially as set forth.

In testimony whereof I affix my signature in 20 presence of two witnesses.

PHILIP MURTHA.
